MOLDING FOR USE AS A DOOR JAMB

Gary A. Hinz, Baton Rouge, La., assignor to
Ethyl Corporation, Richmond, Va.

Filed Mar. 12, 1974, Ser. No. 450,311

Term of patent 14 years

Int. Cl. D25—01

U.S. Cl. D25—74

FIG. 1.

FIG. 2.

FIG. 3.

FIG. 1 is a perspective view of a molding for use as a door jamb showing my new design, the molding being shown broken away to indicate indeterminate length;

FIG. 2 is a top plan view thereof, the molding again being shown broken away to indicate indeterminate length; and

FIG. 3 is a sectional view thereof taken on line 3—3 of FIG. 1.

I claim:

The ornamental design for a molding for use as a door jamb, substantially as shown and described.
